US00D549426S

(12) **United States Design Patent** (10) **Patent No.:** **US D549,426 S**
Fu et al. (45) **Date of Patent:** **** Aug. 28, 2007**

(54) **TUB-SHAPED SNACK**

(75) Inventors: **Bin Fu**, Battle Creek, MI (US); **Don Barnes**, Augusta, MI (US); **Suzanne Annette Devyak**, Battle Creek, MI (US)

(73) Assignee: **Kellogg Company**, Battle Creek, MI (US)

(**) Term: **14 Years**

(21) Appl. No.: **29/261,523**

(22) Filed: **Jun. 15, 2006**

(51) **LOC (8) Cl.** **01-01**

(52) **U.S. Cl.** **D1/122; D1/128; D1/130**

(58) **Field of Classification Search** **D1/121-2, D1/125, 127-30, 199; 426/94, 104, 144, 426/502-3, 510, 549, 559-60, 622, 808**

See application file for complete search history.
